DESIGN FOR A STRIPPING FOR A SHOE

William Lipp, New York, N. Y.

Application March 4, 1938, Serial No. 75,571

Term of patent 3½ years

To all whom it may concern:

Be it known that I, William Lipp, a citizen of the United States of America, residing in city of New York, county of New York, and State of New York, have invented a new, original, and ornamental Design for a Stripping for a Shoe, of which the following is a specification, reference being had to the accompanying drawing, forming part thereof.

Fig. 1 is a front view of a stripping for a shoe showing my new design.

Fig. 2 is a rear view thereof.

My design comprises a series of strips meeting at a central point and giving the appearance of a pleated vamp.

I claim:

The ornamental design for a stripping for a shoe substantially as shown and described.

WILLIAM LIPP.
